Inventor

UNITED STATES PATENT OFFICE.

SAMUEL DOWNS, OF PITMAN, NEW JERSEY, ASSIGNEE OF FORTY-NINE ONE-HUNDREDTHS TO KANDLE BROTHERS, OF PITMAN, NEW JERSEY.

RAILWAY-TIE PLATE.

1,083,599.

Specification of Letters Patent. Patented Jan. 6, 1914.

Application filed September 11, 1913. Serial No. 789,888.

To all whom it may concern:

Be it known that I, SAMUEL DOWNS, a citizen of the United States, residing at Pitman, in the county of Gloucester and State of New Jersey, have invented certain new and useful Improvements in Railway-Tie Plates, of which the following is a specification.

My invention relates to improvements in railway tie plates, the object of the invention being to securely tie the rail and prevent creeping.

A further object is to provide improvements of this character which permit the rail to expand and contract, yet prevent any creeping or movement in any direction.

With these and other objects in view, the invention consists in certain novel features of construction, combinations and arrangements of parts as will be more fully herein-after described and pointed out in the claims.

In the accompanying drawings: Figure 1 is a plan view illustrating my improvements. Fig. 2 is a view in section on the line 2—2 of Fig. 1. Fig. 3 is a view in section on the line 3—3 of Fig. 1, and Fig. 4 is a view in section on the line 4—4 of Fig. 1.

1 I represents a tie and 2 a rail extending across the same. Between the rail 2 and the tie 1, my improved tie plate 3 is located, and is provided on its under face with longitudinal webs 4 which become embedded in the tie and prevent lateral movement of the tie plate. The plate 3 is also provided with spike holes 5 for the reception of ordinary spikes 6 which bind against the base flanges of the rail as clearly shown. On 10 the tie plate 3, at one side of the rail 2, I provide a block 7 which has a serrated or toothed edge 8 located against one base flange of the rail. This block 7 is secured in place by bolts 9 which project through 15 tie plate 1 and have nuts 10 screwed on their upper ends against the block 7. As shown clearly in Fig. 3, the heads 11 of these bolts are on the under face of the tie plate and the tie is recessed as shown at 12 to 20 accommodate them. The bolts have angular portions 13 which project through angular openings 14 in the tie plate so as to prevent any rotary movement of the bolts, allowing the nuts to be screwed tightly into place. 25 On the tie plate 3, at the opposite side of rail

2, I provide two dogs 15 and 16 which are pivotally supported on bolts 17 corresponding to the bolts 11 and nuts 18 are screwed onto the bolts above the dogs to hold the latter in position. These dogs 15 and 16, 60 at their inner wider ends are curved in the arc of a circle and provided with inclined teeth 19 to engage the base flange of the rail.

The outer ends of the dogs 12 are provided with screw-threaded pins 20 which are connected by a turn buckle 21. The pins 20 are threaded in opposite directions, so that when the turn buckle is operated, the dogs 16 will be moved on their pivots 70 so as to properly adjust them to grip the base flange of the rail or to release the rail whenever desired. The turn buckle 21 has openings 22 therein for the reception of a pin to turn the same, and by means of 75 this turn-buckle, any desired engagement of the dogs with the rail may be had.

It will be noted that the teeth of the dogs 15 and 16 are beveled, so that they engage oppositely. In other words, the dog 15 prevents movement of the rail 2 in one direction, while the dog 16 prevents movement of the rail in the other direction, yet when the rail expands or contracts, the particular dog effected will pivot sufficiently to allow 85 for this movement.

Various slight changes might be made in the general form and arrangement of parts described without departing from my invention, and hence I do not limit myself to 90 the precise details set forth, but consider myself at liberty to make such changes and alterations as fairly fall within the spirit and scope of the appended claims.

Having thus described my invention, what I claim as new and desire to secure by Letters Patent is:

1. A railway tie plate having two pivoted dogs, said dogs engaging the same base flange of the rail, and means connecting the outer portions of the dogs for simultaneously operating the dogs to adjust their engagement with the rail, substantially as described.
2. A railway tie plate having a toothed block secured thereto and adapted to engage one side of a rail, two pivoted dogs secured to the tie plate and having curved toothed ends engaging the opposite side of the rail, and means for adjusting the pres- 110

sure of the dogs against the rail, substantially as described.

3. A railway tie plate having a toothed block secured thereto and adapted to engage one side of a rail, two pivoted dogs secured to the tie plate and having curved toothed ends engaging the opposite side of the rail, threaded pins on the dogs, and a turn buckle engaging the pins and operating to adjust the dogs, substantially as described.

4. A railway tie plate having bolt openings therein, bolts projected through said openings, a block having openings receiving two of said bolts, nuts on said last-mentioned bolts locking the block to the plate, said block having a toothed edge engaging one base flange of a rail, two dogs pivotally supported on other of said bolts, nuts on said last-mentioned bolts screwed against the dogs, said dogs at one end curved and

having teeth on said curved ends engaging the base flange of the rail, threaded pins connected to the dogs at their other ends, and a turn buckle engaging said threaded pins, substantially as described. 25

5. A railway tie plate having angular openings therein, bolts having angular portions positioned in said angular openings, dogs pivotally supported between their ends on said bolts, said dogs having curved ends, and beveled teeth on the curved ends of the dogs, said dogs positioned at an angle to each other, and adjusting means connecting the dogs, substantially as described. 30 35

In testimony whereof I have signed my name to this specification in the presence of two subscribing witnesses.

SAMUEL DOWNS.
